INTERCOMMUNICATING CIRCUIT

Raymond Carter Bradford, Hamden, and George Clifford Clark, West Haven, Conn., assignors to American Telephone and Telegraph Company, a corporation of New York

Application July 23, 1940, Serial No. 346,966

5 Claims. (Cl. 179—1)

This invention relates to intercommunicating circuits by which one subscriber may telephone to another, and more particularly to signaling arrangements to be used in connection with said circuits.

It is an object of the present invention to provide an intercommunicating telephone circuit so arranged that either subscriber may signal the other by the use of a minimum amount of apparatus.

It is a further object of the invention to provide a signaling arrangement of the kind above described which is so designed that when one subscriber hangs up before the other at the end of a conversation, a false signal will not result.

The invention may now be more fully understood by reference to the accompanying drawing, the figure of which shows a preferred embodiment of the invention.

Referring to the drawing, S_1 and S_2 schematically indicate two subscribers' stations arranged for intercommunication over conductors T_1 and R_1 leading from the station S_1 , and conductors T_2 and R_2 leading from the substation S_2 . At an intermediate point the signal-controlling arrangements are provided and these consist of double-wound relays SR_1 and SR_2 through the impedance of which talking battery is supplied to the substations from the battery leads BL . At each subscriber's station a buzzer is provided, the buzzer at station S_1 being designated B_1 and that at station S_2 being designated B_2 .

The invention will now be more readily understood from a description of its operation, which is as follows:

Let us assume that the subscriber S₁ desires to call the subscriber S₂. By closing the controlling switch at his station, subscriber S₁ causes current to flow from the positive lead of the battery through the upper winding of relay SR₁, over the conductor T₁ to subscriber's station S₁, and thence back over the conductor R₁ and through the lower winding of relay SR₁ to the negative side of the battery. This energizes the relay SR₁, which at its outermost upper contact closes a circuit from ground over the innermost lower contact of relay SR₂, and over the contact and through the winding of buzzer B₂ to battery. The buzzer B₂ now operates and the subscriber at station S₂ is informed that he is being called.

Upon the subscriber at station S_2 operating his switch to answer the call, current flows from the positive conductor of the battery leads BL , through the upper winding of relay SR_2 , over the conductor T_2 to the subscriber's station S_2 , and

back over the conductor R_2 , and through the lower winding of relay SR_2 to the negative side of the battery. This energizes relay SR_2 which at its innermost lower contact now opens the circuit previously described for the buzzer T_2 , thus bringing the signal to an end. At its outer upper contact relay SR_2 prepares a circuit for the buzzer B_1 , but this circuit is held open at the innermost lower contact of the relay SR_2 which is already energized.

It will be noted that as soon as both relays SR₁ and SR₂ are energized the conductors T₁ and R₁ are directly connected to the conductors T₂ and R₂ over the innermost upper contacts and outermost lower contacts of relays SR₁ and SR₂, and that talking battery is now supplied to both substations through the impedances of the windings of said relays.

It will also be evident that by means of the connections just described the relay SR₁, whose circuit was completed at the subscriber's station S₁, is locked up over the contact at the subscriber's station S₂. The circuit may be traced from the positive conductor of battery leads BL through the upper winding of relay SR₁, innermost upper contact of relay SR₁, innermost upper contact of relay SR₂, over the conductor T₂ to substation S₂, and thence back over the conductor R₂, over the outermost lower contact of relay SR₂, outermost lower contact of relay SR₁, and thence through the lower winding of relay SR₁ to negative battery.

In a similar manner the relay SR_2 , which is normally energized over the contact of the station S_2 , is locked up over the contact of the station S_1 , the connections being as follows: From positive conductor of battery leads BL , through the upper winding of relay SR_2 , innermost upper contact of relays SR_2 and SR_1 , over the conductor T_1 , through the subscriber's station S_1 , back over the conductor R_1 , over the outermost lower contacts of relays SR_1 and SR_2 and thence through the lower winding of relay SR_2 to the negative side of the battery.

45 These locking circuits prevent false operation of the signals when the subscribers hang up. For example, if the subscriber at S₂ hangs up, the relay SR₂, controlled by his station, will not be released as it is locked up over the circuit, just described which is controlled by the substation S₁. As long as the circuit at station S₁ is closed both relays SR₁ and SR₂ will remain energized. When both of these relays are energized both buzzer circuits are held open at the innermost lower contacts of said relays. As soon, however,

as the subscriber at station S_1 opens his switch, relay SR_1 releases (the previously described locking circuit through relay SR_1 was opened at the contact of the subscriber's station S_2) and the relay SR_2 is deenergized at the same time because the locking circuit for said relay over the contact of the substation S_1 is opened. Both relays, therefore, release at the same time and no false signal by either buzzer is possible.

It will be obvious, of course, that if no locking circuits had been provided for relays SR_1 and SR_2 , and the subscriber at S_2 released his circuit before the subscriber at S_1 hung up, relay SR_2 would have been released while relay SR_1 still remained energized, with the result that the circuit previously traced for the buzzer B_2 would be actuated. Similarly, if the subscriber S_1 released his circuit ahead of the subscriber S_2 , relay SR_1 would be deenergized while relay SR_2 would remain pulled up, thus completing a circuit for the buzzer B_1 over the outermost upper contact of the relay SR_2 and the innermost lower contact of the relay SR_1 .

To recapitulate: When both subscribers' circuits are completed, relays SR_1 and SR_2 are each locked up over contacts of both relays through opposite subscribers' sets. If one subscriber hangs up ahead of the other, the locking circuit of the relay of the other subscriber is opened, but the normal energizing circuit of said relay is still closed by the opposite subscriber. The subscriber first hanging up cannot release his own relay because it remains locked up over the contacts of both relays and over the contact of the opposite subscriber's set. Therefore, no false operation of the signal can take place. When, however, the opposite subscriber releases his circuit, both relays are released simultaneously and the apparatus is in normal condition.

It will be obvious that the general principles herein disclosed may be embodied in many other organizations widely different from those illustrated without departing from the spirit of the invention as defined in the following claims.

What is claimed is:

1. In a telephone system, a line, a station at each end thereof, relay means for each station respectively actuated by closure of the line thereat, a signal device at each station responsive to actuation of the relay means of the distant station and disabled in response to actuation of the near relay means, and means effective upon actuation of both relay means to maintain both relay means actuated until the line is opened at both ends.

2. In a telephone system, a pair of stations, a line therebetween and terminating in normally

open switch contacts in said line at each station, a relay for each station having a winding in series with the line, a source of direct current in bridge of said line intermediate said relays, said relays being adapted to individually operate in response to closure of the respective station switch contacts, a signal device at each station adapted to be actuated in response to operation of the relay of the distant station and disabled in response to operation of the near relay, and means effective upon operation of both relays to maintain both relays operated until the switch contacts at both stations are opened.

3. In a telephone system, a pair of stations, a line therebetween, a pair of relays associated with said line and adapted to be operated one from each station, a signal device at each station, said relays so controlling said signal devices that when one of the relays is actuated from one of the stations the signal at the other station will be operated until the other relay is actuated from said other station, and means effective upon operation of both relays to maintain both relays locked up so that neither can be released until the line is opened at both stations.

4. In a telephone system, a pair of stations, a line therebetween, a pair of relays associated with said line and adapted to be operated one from each station, a signal device at each station, said relays so controlling said signal devices that when one of the relays is actuated from one of the stations the signal at the other station will be operated until the other relay is actuated from said other station, and means effective upon actuation of both relays to lock up said relays so that when the line is opened at one station the relay controlled thereby will remain locked up through the other station, and both relays will be simultaneously released when the line is opened at said other station.

5. In a telephone system, a pair of stations, a line therebetween, a pair of relays associated with said line and so arranged that talking battery is supplied to said line through the impedance of said relay windings, said relays adapted to be operated one from each station, a signal device at each station, said relays so controlling said signal devices that when one of the relays is actuated from one of the stations the signal at the other station will be operated until the other relay is actuated from said other station, and means effective upon actuation of both relays to maintain both relays locked up, so that neither can be released until the line is opened at both stations.
